UNITED STATES PATENT OFFICE

BERTRAM L. WATKIN, OF SYRACUSE, NEW YORK, ASSIGNOR TO PASS & SEYMOUR, INC.,
OF SYRACUSE, NEW YORK, A CORPORATION OF NEW YORK

DESIGN FOR A WALL SCONCE

Application filed May 26, 1932. Serial No. 43,905. Term of patent 3½ years.

To all whom it may concern:

Be it known that I, BERTRAM L. WATKIN, a citizen of the United States, and resident of Syracuse, county of Onondaga, and State of New York, have invented a new, original, and ornamental Design for a Wall Sconce, of which the following is a specification, reference being had to the accompanying drawing, forming a part thereof, and in which:

Figure 1 is a perspective view of a wall sconce according to the present design;

Figure 2 is a plan view thereof; and

Figure 3 is a fragmentary section on line 3—3 of Figure 1.

I claim:

The ornamental design for a wall sconce substantially as shown.

BERTRAM L. WATKIN.
